ROTARY HAMMER

Filed May 19, 1926

INVENTOR
NELSON P. RIDGWAY

BY
Richard J. Cook
ATTORNEY

UNITED STATES PATENT OFFICE

NELSON P. RIDGWAY, OF TACOMA, WASHINGTON

ROTARY HAMMER

Application filed May 19, 1926. Serial No. 110,189.

This invention relates to rotary hammers, and the principal object of the invention residing in the provision of air cushions for checking the rebound of the hammers after they have struck the tool and for retarding the return of the hammers into striking position so as to reduce vibration, and shock and thereby provide a more durable and more easily handled device.

10 A further object of the invention is to connect the cylinders wherein the hammers are contained by means of an air tube so that the rebound of the hammer in one cylinder will drive air into the cylinder containing 15 the other hammer to force the latter hammer into striking position.

Other objects reside in the various details of construction and combination of parts as will be fully described in the following 20 specification.

In accomplishing the various objects of the invention, I have provided the improved details of construction, the preferred forms of which are illustrated in the accompanying 25 drawings wherein—

Figure 1 is a side view of a device embodied by the present invention; a side of the housing thereof being removed and parts being shown in section for better illustration.

30 Figure 2 is a horizontal, sectional view taken on the line 2—2 in Figure 1.

Figure 3 is a sectional view taken on the line 3—3 in Figure 1.

35 Referring more in detail to the drawings—

1 designates an enclosing housing made up of opposite side sections 2 and 3 that are joined by means of a plurality of bolts 4 extended through the peripheries of the sections and through an interposed spacing ring 5. At one side of the casing is an extension 6 in which a tubular bushing 7 is fixed by means of a set screw 8; the bushing 45 slidably containing the shank 9 of a riveting tool, drill bit, or other instrument, designated at 10, that may be operated by the striking of blows in rapid succession against its inner end.

50 Extending centrally through the housing

is an operating shaft 11 supported rotatably by ball bearings 12 contained in ball races formed in collars 13 that are fixed on the shaft, and in annular bearings 14 that are fixed to the sections 2 and 3 forming the opposite sides of the housing. Driving connection may be made with either end of the shaft 11 by any suitable means, such as a flexible shaft.

55 Fixed on the shaft 11, in a plane that is perpendicular thereto and centrally between the sides of the housing, is a rectangular plate 15 that forms the hammer body. Fixed in parallel relation to opposite edges of the plate are cylinders 16 in which hammers 17 are slidably fitted, each hammer being provided at its outer end with a reduced, impact shank 17A that extends slidably through the outer end wall of its cylinder. During 60 operation of the device, the hammer elements are moved by centrifugal force to the outer ends of their cylinders into positions at which the ends of the shanks 17A will be caused to impact with the inner end of the mounting shank of the tool 10 so as to effect 65 the hammering operation. The cylinders 16 are so mounted that the axial line of the hammers and the axial line of the shank of the tool will practically coincide at the time 70 of the impact.

75 The inner end of the cylinders 16 are closed by caps 18 to provide closed air chambers 19 at the inner ends of the hammer elements. Each cap is provided with a ball chamber 20 opening directly into the chamber 19 and these chambers 20 are connected by means of a tube 30 through which air compressed and displaced by inward movement of the hammer in one cylinder may be forced into the chamber 19 of the other cylinder to drive its 80 hammer element outwardly into impact position. Valve ports 21 are provided in the outer ends of the ball chambers and ball checks 22 are contained in the chambers to close these 85 ports during inward travel of the hammers but which open to admit air as the hammers move outwardly.

90 As a means of retarding the outward throw of the hammer elements by centrifugal force after impact and rebound, I have provided 95

for trapping air between the outer ends of the body portions of the hammer elements and the outer end walls of their containing cylinders; this being accomplished by making the 5 diameters of the shanks 17A substantially less than that of the diameters of the hammer bodies thereby providing the air pockets, as designated at 28, within the outer end walls of the cylinders. After a hammer element 10 has been brought into impact with the shank 7 of the tool and has rebounded, it will be moved outwardly again by the forcing of air into the end of its cylinder through tube 30 and also due to the centrifugal force incidental 15 to rapid rotation of the device and, as it moves outwardly in its cylinder the trapped air in pocket 28 retards its movement so that it moves easily into position and does not strike with considerable force against the end 20 wall of the cylinder and thereby cause jolt, vibration and ultimate self destruction.

While the tube connection 30 is not absolutely necessary to effective, satisfactory operation of the hammer elements where they 25 are so disposed that centrifugal force will return them to impact position, it is desirable in machines where the hammers are of such length that centrifugal force is minimized to such an extent that it can not be depended 30 upon to return them.

A handle of suitable character, such as is shown at 35, may be provided for holding the device when in use and this may be fixed between the opposite sides of the housing, as is 35 shown in Figure 1.

With the device so constructed, the jolt and jar of operation is reduced to a minimum and a more satisfactory and longer lived tool is provided.

40 Having thus described my invention, what I claim as new therein and desire to secure by Letters-Patent, is:

1. A hammer comprising a rotating hammer body, a pair of cylinders fixed in parallel 45 relation to opposite edges of the said body, hammer elements slidably fitted in said cylinders and having impact shanks extending from their outer ends through the outer end walls of the cylinders, and a tube connecting 50 the inner ends of the cylinders through which air may be driven from one cylinder due to rebound of the hammer therein into the other cylinder to move its hammer out to impact position.

55 2. A hammer comprising a housing mounting a drill bit or the like, a hammer body rotatably mounted in the housing and having a driving shaft, a pair of cylinders fixed in parallel relation to opposite edges of the body, hammer elements slidably fitted in said cylinders, each having an impact shank of reduced diameter extending therefrom through the outer end of its cylinder into position for impact with the said drill bit, 60 said cylinders providing air cushions at op-

posite ends of the hammer elements, and a tube connecting the inner ends of the two cylinders.

3. A hammer comprising a rotating hammer body, a pair of cylinders fixed in parallel 70 relation to opposite edges of the body, hammer elements slidably fitted in the cylinders and having impact shanks extending from their outer ends through the outer end walls of the cylinders, air inlet valves provided at 75 the inner ends of the cylinders and a tube connecting the inner ends of the cylinders through which air may be driven from one cylinder to the other.

Signed at Tacoma, Washington, this 30th 80 day of March, 1926.

NELSON P. RIDGWAY.
